EXTENSIBLE SPRING-RETRACTED KEY HOLDER OR SIMILAR ARTICLE

John J. Evans, Jr., Westfield, N.J., assignor to Evans-Aristocrat Industries, Inc., Elizabeth, N.J., a corporation of New Jersey

Filed July 14, 1965, Ser. No. 86,146

Term of patent 14 years

(Cl. D17—14)

FIG. 1

FIG. 2

FIG. 3

FIG. 4

FIG. 5

FIG. 6

FIG. 1 is a top view of an extensible spring-retracted key holder showing my new design;

FIG. 2 is a front view thereof;

FIG. 3 is a side edge view thereof, both side edges having the same appearance;

FIG. 4 is a rear view thereof;

FIG. 5 is a bottom view thereof; and

FIG. 6 is a fragmentary sectional view on a larger scale on the line 6—6 of FIG. 2.

I claim:

The ornamental design for an extensible spring-retracted key holder or similar article, substantially as shown and described.
